UNITED STATES PATENT OFFICE.

NATHAN A. LEVITAN, OF BROOKLYN, NEW YORK, ASSIGNOR TO J. J. BRAZE CO., OF NEW YORK, N. Y., A COPARTNERSHIP COMPOSED OF J. J. BRAZE AND N. A. LEVITAN.

DESIGN FOR A BRIDGE-LAMP ARM.

Application filed May 22, 1926. Serial No. 17,813. Term of patent $3\frac{1}{2}$ years.

To all whom it may concern:

Be it known that I, NATHAN A. LEVITAN, a citizen of the United States, residing at Brooklyn, county of Kings, city and State of New York, have invented a new, original, and ornamental Design for a Bridge Lamp Arm, of which the following is a specification, reference being had to the accompanying drawing, forming part thereof.

In the drawing the figure is an elevation showing a bridge lamp arm made in accordance with my invention.

I claim:

The ornamental design for a bridge lamp arm, as shown.

NATHAN A. LEVITAN.
